THREE-ROLL MILL AND MECHANISM FOR ADJUSTING THE INTERMEDIATE ROLL

Eric Procter Beach, Barrow-in-Furness, and George Lockley, Ulverston, England, assignors to Vickers-Armstrongs (Engineers) Limited, London, England, a British company

Application August 21, 1956, Serial No. 605,367

Claims priority, application Great Britain August 22, 1955

5 Claims. (Cl. 241—111)

This invention relates to three-roll mills of the kind which are arranged so that material to be ground is passed firstly between one roll and a second roll and then between the second roll and a third roll, the axes of the three rolls being parallel.

According to the present invention there is provided a three-roll mill of the kind referred to in which the second roll is carried by adjusting mechanism arranged for moving the second roll towards or away from a plane that includes the axes of said one and third rolls, whereby the clearances between the second roll and each of the other two are simultaneously decreased or increased respectively, the adjusting mechanism also being arranged for moving the second roll towards and away from each of the other two rolls individually, so that the clearance between said one and said second roll can be increased whilst at the same time the clearance between said second and said third rolls is decreased, and vice versa.

It is to be understood that in some cases the second roll may contact the other two rolls so that there are no clearances between the rolls. Where this is so references to "increase or decrease of clearance" should be replaced by "decrease or increase of pressure."

For a better understanding of the invention, and to show how the same may be carried into effect, reference will now be made to the accompanying drawings, in which:

Figure 1 is a sectional side elevation of part of a three-roll mill, the section being taken on line I—I of Figure 2 and certain parts being omitted.

Figure 2 is a part sectional front elevation of the mill of Figure 1, the section being taken on line II—II of Figure 1 and certain parts being omitted, and

Figure 3 is a sectional view taken on the line III—III of Figure 1.

The mill has a bed (not shown) that carries two side frames 1, 2 (shown in chain-dot outline) by which the three rolls 3, 4 and 5 of the mill are carried. The three rolls 3, 4, 5 are of the same diameter and their axes are parallel. The rolls 3 and 5 are rotatably mounted directly in the side frames 1, 2 and rotate about fixed centres 6, 7 respectively. The roll 4 is spaced laterally from the roll 3 and is slightly higher than the roll 3, the distance between the axes of centres 6 and 7 of the rolls 3 and 5 being slightly less than twice the diameter of one of the rolls, so that the roll 4 cannot pass between the rolls 3 and 5. The central roll 4 is carried, with its centre 8 above the plane joining the axes 6 and 7 of the rolls 3 and 5, by two bearings 9, the housings 10 of which are supported by mechanism that permits adjustment of the roll 4 with respect to the rolls 3 and 5. Each housing 10 has two upwardly directed arms 11 that are pivotally secured by a pin 12 to an arm 13 of a bellcrank lever 14. The bellcrank lever 14 is pivotally secured to the adjacent side frame 1 or 2 by a pin 15 parallel to the axes of the rolls 3, 4 and 5. The arm 13 effectively extends approximately horizontally and the other arm 16 of the bellcrank lever 14 extends approxi-

2

mately vertically upwardly. The free end 16A of the arm 16 is bifurcated and rotatably carries a pin 17 that is parallel to the roll axes 6, 7, 8. The pin 17 has a threaded hole 18 therethrough perpendicular to the axis of the pin 17 and a long horizontal bolt 19 is threadedly engaged in this hole 18. The free end of the bolt 19 is passed through and threadedly engages with a pin 20 which is parallel to the pin 17. The pin 20 is rotatably mounted in an upright lever 21, the lower end of which is pivotally secured by a pin 22 to the adjacent side frame 1 or 2. The bolt 19 is passed through holes 21A in the lever 21, these holes being tapered to permit relative angular movement of the lever 21 and bolt 19 about the axis of the pin 20. The upper end of the lever 21 has a vertical slot 23 in which a sliding block 24 is located. An eccentric pin 25 on one end of a cross-shaft 26 is engaged in a hole 27 in the sliding block 24. The cross-shaft 26, which is parallel to the roll axes 6, 7 and 8, is supported by the two side frames 1 and 2 and has two eccentric pins 25, one at each end thereof, for co-operating with the sliding blocks 24 at each end of the roll 4. The shaft 26 has a downwardly extending lever 28 keyed thereto near the right-hand end (Figure 2) of the shaft 26. The free end of this lever 28 is pivotally secured to 20 one end of an adjusting link 29 disposed parallel to the bolts 19. The other end of the link 29 is pivotally secured to the free end of an upwardly extending lever 30 keyed to a shaft 31 that is mounted in the side frame 1 and has an approximately horizontal operating handle 32 fixed thereon. This handle 32 has ratchet and pawl mechanism 33 associated therewith for securing the mechanism associated with the sliding blocks 24 in any desired position.

Each bearing housing 10 has an arm 34 extending 35 downwardly therefrom in a direction diametrically opposite to that of the arms 11. A slot 35 extends from the free end of the arm 34 towards the axis 8 of the roll 4. A sliding block 36 is located in this slot 35 and an eccentric pin 37 on a short shaft 38 pivotally supported in the adjacent side frame 1 or 2 passes through a hole 39 in this sliding block 36. The short shaft 38 is parallel to the roll axes 6, 7 and 8 and has a gear segment 40 keyed thereto, this gear segment 40 co-operating with a worm 41 that is fixed on a shaft 42 carried by brackets 43 attached to the adjacent side frame 1 or 2. The shaft 42 is horizontal and has a handwheel 44 thereon.

It will be understood, therefore, that the adjusting mechanism has one operating handle 32 and two hand-wheels 44 for adjusting the position of the centre roll 4.

The mill described above is used for grinding materials used, for example, in the paint, printing-ink, chocolate, soap and plastic industries. The centre roll 4 is brought into, or almost into, contact with the rolls 3 and 5 by operation of the handle 32 and the material is 50 passed firstly between the rolls 3 and 4 and is subsequently passed between the rolls 4 and 5, the material being ground as it passes between the rolls. Movement of the operating handle 32 downwardly causes the free ends of the arms 13 of the bellcrank levers 14, to be moved upwardly through the lever and link arrangements 55 that include the shaft 31, lever 30, link 29, lever 28, shaft 26, eccentric pins 25, blocks 24, levers 21 and bolts 19. The centre roll 4 is thus withdrawn from the rolls 3 and 5, the centre roll 4 being guided during such upward movement by the slots 35 in the arms 34 which 60 slots 35 slide on the blocks 36 that are at this time in a fixed position. When the operating handle 32 is moved upwardly the centre roll 4, through the intermediary of said lever and link arrangements, is moved downwardly until it contacts or almost contacts the rolls 3 and 5. The pressures or clearances between the rolls 3 and 4 and 65 between the rolls 4 and 5 are adjusted by operation of the 70 other arm 16 of the bellcrank lever 14.

the two handwheels 44. When the two handwheels 44 are turned in one direction, the gear segments 49 cause the eccentric pins 37 on the short shafts 39 to swing in an arc towards the roll 3, the roll 4 swinging about the axis of the pins 12 that connect the arms 11 and the bellcrank levers 14. Hence the clearance between the rolls 3 and 4 is decreased (or the pressure increased) whilst the clearance between the rolls 4 and 5 is increased (or the pressure decreased). When the two handwheels 44 are turned in the opposite direction the roll 4 is moved to decrease the clearance (or increase the pressure) between the rolls 4 and 5 and increase the clearance (or decrease the pressure) between the rolls 3 and 4.

Although in the embodiment described above the second roll is adjusted through the intermediary of mechanical linkages, it is to be understood that the second roll could, if desired, be moved through the intermediary of other means, for example, hydraulic mechanism.

We claim:

1. A three-roll mill comprising first, second and third rolls arranged in series the axes of which are parallel, the first and third rolls being mounted for rotation about fixed axes, the axis of the second roll being offset with respect to a plane which includes the axes of the first and third rolls and the diameter of the second roll being greater than the shortest distance between the first and third rolls, adjusting mechanism carrying said second roll for moving the second roll toward and away from the plane that includes the axes of the first and third rolls to respectively and simultaneously decrease or increase the clearances between the second roll and each of the other two rolls, the adjusting mechanism including means for moving the second roll toward and away from each of the other two rolls individually, whereby the clearance between the first and second rolls can be increased while the clearance between the second and third rolls is simultaneously decreased, and vice versa.

2. A mill as claimed in claim 1, wherein the second roll is carried at each end thereof by a bearing, the housings of the bearings being pivoted about a pivot axis offset to one side of the axis of the second roll, and wherein each housing at the opposite side of the axis of

the second roll is connected to the adjusting mechanism through a pin and slot connection, the slot being directed towards the axis of the second roll, and the adjusting mechanism being arranged for moving said pivot axis towards and away from said plane and for moving the pin and slot connections towards and away from said other two rolls individually.

3. A mill as claimed in claim 2, wherein the slot of each pin and slot connection is in the associated housing, the pin being constituted by a block extending in the slot and connected to the adjusting mechanism for movement towards and away from said other two rolls, the arrangement being such that when the pivot axis is moved towards or away from said plane the housings slide on said blocks and such that when the blocks are moved the housings pivot about said pivot axis.

4. A mill as claimed in claim 3, wherein the adjusting mechanism includes a single manually operated member for adjusting the position of said pivot axis and two manually operated members, one for each of said connections, for adjusting the positions of the latter individually.

5. A mill as claimed in claim 1, wherein the second roll is carried at each end thereof by a bearing, the housings of the bearings being pivoted about a pivot axis offset to one side of the axis of the second roll, each housing at the opposite side of the axis of the second roll being connected to the adjusting mechanism through a pin and slot connection, the slot being directed towards the axis of the second roll, the adjusting mechanism being arranged for moving said pivot axis towards and away from said plane and for moving the pin and slot connections towards and away from said other two rolls individually, and the adjusting mechanism including a single manually operated member for adjusting the position of said pivot axis and two manually operated members, one for each of said connections, for adjusting the positions of the latter individually.
